UNITED STATES PATENT OFFICE

JACKSON L. KAIL, OF CHICAGO, ILLINOIS.

ELEVATOR-DOOR.

No. 895,467.

Specification of Letters Patent. Patented Aug. 11, 1908.

Application filed July 15, 1907. Serial No. 383,777.

To all whom it may concern:

Be it known that I, JACKSON L. KAIL, a citizen of the United States, residing in the city of Chicago, in the county of Cook and State of Illinois, have invented certain new and useful Improvements in Elevator-Doors, of which the following is a full, clear, and exact description.

My invention relates to certain new and useful improvements in elevator doors, the object being to provide a door adapted to open and close the openings in the elevator inclosure at the various floors, and so arranged that all of the openings, with the exception of the one at the floor where the elevator car happens to be, shall always be closed and the closure locked.

Another object is to provide a door that is operated by the movement of the car to open and close the same.

Another object is to provide a device in which the door opening is positively closed by the car as the latter leaves the opening.

To such end the invention consists in a flexible door adapted to cover at all times all of the door openings in the inclosure with the exception of the one in front of the car and so arranged that the car shifts the passage way in the door from floor to floor as the car travels from floor to floor.

It further consists in means for locking the door at the various floors and for unlocking it in front of the car as the latter moves along.

Other objects and advantages will appear in the course of this specification and the essential features will be more definitely pointed out in the claims.

The invention is fully described in this specification and clearly shown in the accompanying drawings in which

Figure 1 is a front view of an elevator inclosure, with my improved door applied thereto. Fig. 2 is a vertical section thereof taken on the line 2—2—Fig. 1. Fig. 3 is a front view of an elevator car, a fragment of the door and certain parts of the door operating mechanism. Fig. 4 is a horizontal section through the elevator inclosure and well, taken on the line 4—4—Fig. 1. Fig. 5 is a perspective view of a fragment of the door and inclosure certain sheaves and roller being shown in dotted lines. Fig. 6 is a fragmental plan view of certain door operating

mechanism, and Fig. 7 is a plan view of certain door operating mechanism located below the car.

In these views A indicates an elevator inclosure of suitable ornamental design, and containing the usual door openings a , a^1 , a^2 , a^3 located at the different floors a^4 , a^5 , a^6 , a^7 , of the building. The elevator car B, is carried by the cables b, in the usual manner and is guided upon vertical guides a^8 as is common in elevators of this class. The elevator car is preferably provided with a gate, b^1 , which may be of any well known type, and adapted to be moved by the elevator conductor to open or close the opening in the front of the car. In freight elevators this gate may be dispensed with, but it serves the purpose of preventing injury to passengers from contact with the inclosure, or from falling out of the elevator car.

The door openings are adapted to be covered by a flexible door C which extends down through the well, and is connected at the top and bottom to the elevator inclosure or other substantial frame work of the building. As shown this door is supported upon a bar 10, at the top of the inclosure and hangs down in the well immediately behind the front wall of the inclosure, and extends past all of the door openings therein, except the one in front of the car, where it is carried around and behind said car by means of rollers, 20, 21, 22, 23, supported by the car, as hereafter set forth. This provides a door which closes every door opening in the inclosure except at the point immediately in front of the car, where a gap is left through which the car may be entered or left.

The door comprises a plurality of flexible members, here shown as cables 11, which extend from the top to the bottom of the well, and are clamped to the bar 10, at the top thereof, by means of clamps 10^a. The cables are also clamped at their lower ends to a bar 10^b by means of clamps 10^c. Cross bars 12, are clamped to the cables 11, as by hook bolts 12^a, and said cross bars may be of ornamental design to give a pleasing appearance to the door and they are spaced apart at regular intervals, the distance between them being regulated as desired. The cables form flexible connections between the cross bars and together with said cross bars form the door closure—that is the

cables and bars close the door openings. The cables serve to support and space the bars apart and the bars serve to space the cables, so that they cannot be spread apart in front of the door opening. The cross bars extend beyond the body of the door device, thus forming lateral projections which co-operate with other devices to prevent transverse movement of the flexible door, except at the point where it is carried around the car, so that it is impossible for one to force the door into the well.

As shown the mechanism for locking the door in place comprises a pair of locking cables 13, that extend along the side edges of the door and between which cables and the door casings a^9 , the cross bars 12, are confined whereby forward or backward movement of the door is prevented at any point except at the car. A plurality of stops or shoulders 14, are secured to the door casings a^9 which stops lie between the ends of the adjacent cross-bars and overhang the cables 13, so as to prevent the latter from being accidentally moved away from the inclosure; consequently the door itself is prevented from being forced into the well by reason of the engagement of the ends of the cross bars, with the braced locking cables 13. The locking cables 13, are however diverted from their course by means of sheaves 15, 16, 15^a, 16^a, which are carried by the car so as to release the door and permit the latter to leave its vertical plane wherever the car happens to be, thus leaving a gap, through which passengers may enter or leave the car. The sheaves 15, 16, 15^a, 16^a, are journaled upon brackets 17, secured upon the top and bottom of the car and as shown said sheaves are so arranged as to carry a bight of the locking cables out of line, (see Fig. 3) thereby leaving a gap in the locking cables through which the cross bars may leave and enter the plane of the door. The cross bars are thus securely held between the door casings and the locking cables, and as the car passes along the locking cables are switched away from the cross bars to allow the door to pass around the car, and then switched behind them as the door again enters the longitudinal plane, thus again locking it in place behind the car as it passes along.

The rollers 20, 21, are journaled in brackets 24 which are mounted upon the arch bar, b^2 , of the elevator car, and the rollers 22, 23 are journaled in brackets 25, 26 mounted upon the beam b^3 , which forms part of the supporting frame of the car. The brackets 25, are pivotally mounted upon the beam b^3 and adjusting screws 25^a are threaded in said arms and bear upon bearing plates 25^b, secured upon the underside of the car. This furnishes means for taking up slack in the cables and for bringing the cross bars into proper relation with the stops 14. The roll-

ers 20, 21, 22, 23 are grooved longitudinally upon their peripheries to admit the cross bars 12 of the cables when passing around the rollers, and the ends of the rollers are provided with grooved flanges 20^c in which run the end cables of the door, said grooved flanges serving to guide the door in its movement around the car.

It is obvious that inasmuch as the cross bars enter the longitudinal grooves in the rollers as they pass around the same, very little if any noise is produced in the operation of the device. The cross bars are preferably mounted adjustably upon the cables so that as the cables stretch the cross bars may be adjusted to place so as to fall in between the adjacent shoulders or stops, 14, on the door casing. Furthermore the entire door may be adjusted vertically by means of the clamps at the top and bottom of the inclosure.

In the operation of the device the car is run up and down in the well the bight in the door passing around the car, leaving a gap or passageway immediately in front of the car through which passengers may enter or leave the car. The gate b^1 being kept closed until the car stops, there is no danger to the passengers in the car from contact with the inclosure or from falling or being pushed out through the door openings at the different floors.

If the car is ascending, the door passes around the rollers 20, 21, 22, 23, in the direction of the arrows, Fig. 2, the locking cables being deflected from their paths by the sheaves 15, 16, 15^a, 16^a, so as to release the cross bars. As the bight again enters into the longitudinal plane of the door at the under side of the car, the locking cables are fed back into place thus locking the door to the inclosure.

I am aware that various alterations and modifications of the device are possible without departing from the spirit of my invention and I do not therefore desire to limit myself to the exact construction shown and described.

I claim as new and desire to secure by Letters Patent.

1. The combination with an elevator inclosure having a plurality of vertically aligned door openings and an elevator car, of a flexible door adapted to close all of said door openings, means for maintaining a gap in said door in front of said elevator car and suitably operated, flexible, locking cables for said door, extending along the door openings.

2. The combination of an elevator inclosure, having a plurality of door openings, a car, a flexible door adapted to close said openings, means upon the car for maintaining a gap in the door adjacent to the car, flexible door locking cables engaging said door to lock the same to the inclosure and means upon the car for maintaining the cables in

- disengaged condition with respect to the door at a point adjacent to the car, regardless of the vertical position of the car.
3. Elevator door mechanism, comprising an elevator inclosure having a series of vertically aligned door openings, an elevator car, a flexible door constructed and arranged to extend past all of the door openings except one at any given time, means upon the car for maintaining a gap in said door in front of the car, locking cables arranged to lock the door to the inclosure and devices upon the car arranged to actuate said cables to unlock the door at the approach of the car.
4. Elevator door mechanism, comprising an elevator well, having a series of vertically aligned door openings, an elevator car, a flexible door device constructed and arranged to close all of the door openings in the well, rollers upon the car arranged to carry a bight of the door device around the car, locking cables arranged to hold the door device in its longitudinal plane, and sheaves upon the car arranged to shift the locking cables out of engagement with the door device.
5. Elevator door mechanism, comprising an elevator well, having a series of vertically aligned door openings, an elevator car, a flexible door device constructed and arranged to close all of the door openings in the well, except the one in front of the car, and having lateral projections extending beyond the edges of the body of the door, guide rollers upon the car, locking cables engaging the lateral projections, retaining devices for the locking cables, sheaves upon the car for disengaging the locking cables from the lateral projections at the approach of the car, and means for taking up the slack in the cables.
6. Elevator door mechanism, comprising an elevator well, having a series of vertically aligned door openings, an elevator car, a flexible door device constructed and arranged to close all of the door openings in the well, except the one in front of the car, and having lateral projections extending beyond the edges of the body of the door, guide rollers upon the car, locking cables engaging the lateral projections, retaining devices for the locking cables, sheaves upon the car for disengaging the locking cables from the lateral projections at the approach of the car, and means for taking up the slack in the cables.
7. Elevator door mechanism, comprising an elevator well, having a series of vertically aligned door openings, an elevator car, a flexible door device constructed and arranged to close all of the door openings in the well, except the one in front of the car, and having lateral projections extending beyond the edges of the body of the door, guide rollers upon the car, locking cables engaging the lateral projections, retaining devices for the locking cables, sheaves upon the car for disengaging the locking cables from the lateral projections at the approach of the car, and means for adjusting the cross bars upon the cables.
